CLAIM

The ornamental design for weapon stock fore end as shown and described.

DESCRIPTION

FIG. 1 is a lower perspective view of the weapon stock fore end embodying the new design.

FIG. 2 is a bottom view thereof.

FIG. 3 is a right side view thereof.

FIG. 4 is a left side view thereof.

FIG. 5 is an enlarged front view thereof; and,

FIG. 6 is an enlarged rear view thereof.

The evenly spaced broken lines illustrate portions of the weapon stock fore end that form no part of the claimed design. The dash-dot broken lines form the boundaries of the claim. The shaded surfaces between broken and solid lines form no part of the claimed design.

1 Claim, 4 Drawing Sheets
